UNITED STATES PATENT OFFICE.

FRANK J. CALKINS, OF TOLEDO, OHIO.

HANDLE-BAR FOR BICYCLES.

SPECIFICATION forming part of Letters Patent No. 781,128, dated January 31, 1905.

Application filed July 2, 1904. Serial No. 215,194.

To all whom it may concern:

Be it known that I, FRANK J. CALKINS, a citizen of the United States of America, and a resident of Toledo, in the county of Lucas and State of Ohio, have invented certain new and useful Improvements in Handle-Bars for Bicycles, of which the following is a specification.

This invention relates to handle-bars for bicycles, and has for its object to provide an automatically-adjustable improvement whereby the rider can instantly and easily change and adjust each bar either separately or together at will without either having to remove his hands, reduce the speed, or stop the vehicle.

The invention consists in the new and novel constructions and combinations of parts for accomplishing the purpose, substantially as hereinafter described and claimed, and illustrated in the accompanying drawings, in which—

Sheet 1, Figure 1, is a top or plan view of the handle-bar head embodying my invention. Fig. 2 is a horizontal section of the same. Fig. 3 is a face view of the front or name plate. Fig. 4 is a rear view of the same, showing the locking-cogs. Fig. 5 is a detached view of the sliding bolt on which the handle-bars are pivoted. Fig. 6 is a detached view of the spring which forces the said bolt outward. Sheet 2, Fig. 7, is a front view of the handle-bar head, showing the bars in an elevated position. Fig. 8 is a side elevation of the head. Fig. 9 is a vertical section of the head. Figs. 10 and 11 are respectively detached side views of the disk ends of the handle-bars, showing their engaging cogs. Fig. 12 is a vertical section of the front or name plate. Fig. 13 is a detached view of the bolt that holds the said plate onto the head-piece.

A represents the handle-bar head, having a tubular portion A' for attaching it to the handle-bar post. It is provided with an offset A², to which is secured the front or name plate B by means of a bolt b, Fig. 13.

C is a tubular seat for the sliding bolt-spring C'' in the upper part of head A.

The name-plate B has a central opening 50 through which the sliding bolt C is inserted

when putting the parts together. The inside face of the plate B has a series of radial cogs B' at each side of its center and at its outer edge.

D and D' are the handle-bars, each having 55 perforated disks d d'. The disk d' on bar D' is double or bifurcated to receive the single disk d on bar D. Each of said bars D D' are provided with radial cogs d'' d'', designed to mesh with the cogs B' on the plate B for locking 60 the handle-bars in place in any of the positions they may be placed. The perforation in the disk on bar D is screw-threaded for receiving and holding the screw-threaded part of the sliding bolt C, which forms the pivotal joint 65 on which the bars are turned in elevating or lowering them. The handle-bars and this bolt are capable of lateral movement in the head A for the purpose of disengaging the cogs on the bars from the cogs on the front plate B 70 to enable the bars to be elevated or depressed when desired by pulling on the handle-bars rearwardly, the bolt C compressing the spring C'', which normally holds the handle-bars in the forward position, as shown by dotted lines 75 in Fig. 8.

From the foregoing it will be seen that the rider may quickly and easily change the vertical position of the handle-bars by simply pulling rearwardly on the bars, thereby releasing them from the front plate and then elevating or lowering the ends of the bars to any desired position and again returning them to their engagement with the said plate and again locking them. This is readily done 85 without even letting go the hold on the handles or reducing the speed or stopping the vehicle. It is therefore apparent that this is a very ready means for immediately adjusting the handle-bars to any position desired. 90

Having described my invention, what I claim, and desire to secure by Letters Patent, is—

1. In bicycle handle-bars, a head attachable to the handle-bar post, a spring-seat in said head, and a recess for the reception of the pivoted ends of the handle-bars, a front plate attached to the end of the head and having a perforation in line with said spring-seat, handle-bars having perforated disks and radial 95

cogs, radial cogs on the inside face of the said front plate adapted to mesh with the said cogs on the bars, and a bolt through the front plate, the bar-disks and extending into the spring-seat, and a spring in said seat bearing against said bolt, adapted to lock the bars in the head, substantially as described.

2. In bicycle handle-bars, a head, a perforated front plate attached to the head, radial cogs on the inside face of the said front plate, handle-bars having perforated disks and also provided with radial cogs, a slideable pivotal bolt through the front plate and the bar-disks, and having a screw-threaded portion for se-

curing it in one of the bar-disks, its inner end 15 extending into the said spring-seat in the head, and a spring in the head bearing against the bolt, and adapted to be compressed by the rearward movement of the handle-bars for adjusting the handle-bars, substantially as described. 20

Signed by me at Toledo, Ohio, this 28th day of June, 1904.

FRANK J. CALKINS.
